UNITED STATES PATENT OFFICE.

GUSTAV B. WICHMANN AND DAVIS RICH, OF ST. LOUIS, MISSOURI.

MOP.

939,883.

Specification of Letters Patent.

Patented Nov. 9, 1909.

Application filed November 16, 1908. Serial No. 462,904.

To all whom it may concern:

Be it known that we, GUSTAV B. WICHMANN and DAVIS RICH, citizens of the United States of America, residing at the 5 city of St. Louis, in the State of Missouri, have invented certain new and useful Improvements in Mops, of which the following is a full, clear, and exact description, reference being had to the accompanying drawings, forming part of this specification.

Our invention relates to mops for scrubbing floors and it has for its object the production of a mop of this description provided with a clamp head whereby the swab 15 of the mop may be detachably held to the mop handle and rendered rounding in shape to correspond to the most prevalent type of mops and in which the swabs are tied to the mop handle.

By our improvement new swabs may be substituted for the original swabs from time to time with readiness and ease and by a simple operation.

Figure I is an elevation of our improved 25 mop. Fig. II is an enlarged elevation of the mop head. Fig. III is a longitudinal section through the mop head. Fig. IV is an end view of the mop head. Fig. V is a cross section taken on the line V—V of Fig. III. 30 Fig. VI is a perspective view of the draw nut operable on the ferrule of the mop head.

In the accompanying drawings:—A designates the handle of our mop and B the swab which preferably consists of cords such 35 as are commonly used in round mops, but may consist of a cloth or strips of any suitable material.

1 designates the ferrule of the mop head that is fitted to the handle A and secured 40 thereto by any suitable means such as screws 1^a. The ferrule is provided with a screw thread 2 and terminates at its outer end in a bell shaped member 3 that extends beyond the end of the mop handle and at the interior 45 of which are longitudinal grooves 4, (see Figs. III and IV.) In the body of the ferrule and extending in alinement with the grooves 4 are longitudinal slots 5.

6 designates a draw loop that is operable 50 in the grooves 4 and slots 5 and the closed end of which is adapted to project beyond the bell shaped member of the mop head ferrule to receive the swab B which is passed therethrough while the draw loop is in an 55 extended position to permit the ready insertion of the swab through the loop. The

draw loop is provided at its inner ends with outwardly projecting arms 7 which extend laterally through the slots 5 in the ferrule 1.

8 is a carrier ring loosely fitted to the ferrule 1 so that it may be moved longitudinally on said ferrule and which is provided with perforated ears 9 through which the arms 7 of the draw loop may be passed after they have been extended across the body of the 60 ring at its upper edge, the ends of the arms being preferably bent upwardly in engagement with the outer edges of said ears subsequent to the passage of the arms through the ears.

70 10 is a draw nut fitted to the ferrule 1 and preferably provided with wings 11 by which it may be readily turned upon said ferrule. This draw nut is adapted to operate against the carrier ring 8 for the purpose of imparting outward movement to said ring and the draw loop fitted thereto.

75 In the practical use of our mop, the mop swab is introduced into the draw loop 6 when the draw loop is in an extended position to which position it is readily moved by drawing it outwardly subsequent to rotating the draw nut 10 upon the ferrule to move it toward the outer or lower end of the 80 mop head. Then when the swab has been 85 introduced into the draw loop 6 said draw loop is moved inwardly or upwardly to carry the top portion of the swab to the bell shaped member 3 of the mop head ferrule, a movement that is readily accomplished either by 90 a pull upon the carrier ring 8 or by the rotation of the draw nut 10 upon the ferrule to move it in an outward or upward direction. After the swab has been brought to the bell 95 shaped member of the ferrule it is drawn tightly thereto by rotation of the draw nut 10, with the result of causing said draw nut to impart outward or upward movement to the carrier ring and draw loop whereby the 100 swab is spread outwardly due to its engagement with the bell shaped member at the end of the mop head ferrule.

105 The only action necessary in substituting a new swab for one previously in use is that of rotating the draw nut 10 upon the mop head ferrule to move it outwardly or downwardly thereon, and permit the draw loop to be extended in order that the old swab may be withdrawn from the loop and a new one 110 inserted thereinto, after which the new swab is secured in the mop head by the operation of the parts as previously explained.

We claim:—

1. A mop head comprising a ferrule, a slidable swab receiving draw loop extending directly through said ferrule, and means whereby said draw loop may be moved longitudinally of said ferrule so as to pull the draw loop into the latter.
2. A mop head comprising a ferrule, a slidable swab receiving draw loop extending directly through said ferrule, a carrier ring loosely fitted to said ferrule and to which said draw loop is connected, and means operable upon said ferrule whereby said carrier ring may be moved longitudinally of said ferrule so as to pull the draw loop into the latter.
3. A mop head comprising a screw threaded ferrule, a slidable swab receiving draw loop extending directly through said ferrule, a carrier ring loosely fitted to said ferrule

and to which said draw loop is connected, and a screw threaded draw nut operable on said ferrule and adapted to move said carrier ring longitudinally of said ferrule so as to pull the draw loop into the latter.

25

4. A mop head comprising a slotted screw threaded ferrule, a slidable draw loop extending through the slots in said ferrule, a carrier ring loosely fitted to said ferrule and to which said draw loop is connected, and a screw threaded draw nut operable on said ferrule whereby said carrier ring may be moved longitudinally of said ferrule so as to pull the draw loop into the latter.
